His ATTORNEY

UNITED STATES PATENT OFFICE

JOHN B. TEGARTY, OF LAKEWOOD, OHIO, ASSIGNOR OF ONE-HALF TO ARTHUR H. VAN HORN, OF LAKEWOOD, OHIO

AERIAL TOY

Application filed April 14, 1930. Serial No. 444,308.

My invention is an improvement in aerial toys and the method of making the same.

I am aware that aerial toys have been made heretofore by stamping or cutting the various parts, including the fuselage and wings, from sheet material as separate parts and then assembling these parts in their properly related positions. Aerial toys such as gliders formed in this way are usually cut and sold by the manufacturer in knockdown form. So far as I am aware, however, aerial toys such as gliders have not been formed heretofore by simply printing or otherwise defining the outline of the toy on a single sheet of material, whereby the user may construct his own toy by simply cutting around the outline to form a single blank, and then folding portions of the blank to form the fuselage and aerofoils from the said blank.

It is therefore, an object of my invention to increase the educational value of cut out aerial toys such as gliders, by enabling the user to cut from a single sheet, a single blank capable of being formed into a unitary flying structure.

Another object of my invention resides in an improved method of making aerial toys in the form of unitary structures from a single sheet of material.

A further object of the invention is to enable a toy of the above named character to be formed with hollow aerofoils having a predetermined camber.

Another object of my invention is to construct a rigid, sturdy aerial toy from a single cut out blank and to brace the aerofoils against lateral and longitudinal stresses or sudden impacts.

A still further object of the invention is to construct a simple cut out toy as a unitary structure from a single sheet of material on which the outline of the toy may be defined on one side of the sheet only and on which directions for cutting and assembling the toy may be printed. In this manner I have provided a simple article which may be manufactured very inexpensively and which is capable of shipment in flat or rolled form.

Other objects and advantages of my invention will become more apparent as the follow-

ing description of two embodiments thereof progresses, reference being made to the accompanying drawings in which like reference characters are employed to designate like parts throughout the same.

In the drawings—

Figure 1 is a plan view of the preferred embodiment of my invention, showing the sheet of material on which the outline of the aerial toy is defined.

Figure 2 is a side elevation of the toy assembled after being cut from the sheet in Figure 1.

Figure 3 is an end view of one of the aerofoils showing how the same is formed. In full lines I have shown the first step of bending or folding the foil and in dotted lines I have illustrated how the foil sections are secured together to form a cambered aerofoil.

Figure 4 is an end elevation of an assembled aerofoil.

Figure 5 is a plan view of the assembled toy showing the method of supporting and bracing the aerofoils.

Figure 6 is a front elevation of the assembled toy.

Figure 7 is a fragmentary elevation of the fuselage and an aerofoil illustrating a modification of my invention.

Referring first to Figures 1 to 6 inclusive, illustrating the preferred form of my invention, and more particularly to Figure 1 in which I have illustrated the sheet of material on which the outline is defined, I prefer to employ a sheet 1 of flexible material having a suitable texture and thickness, and which is stiff enough to impart ruggedness and rigidity to the toy formed therefrom.

On one face of the sheet an outline of an aerial toy such as a glider monoplane or the like, is defined by any suitable means, as by printing, impressing or partially cutting or otherwise marking the outline thereon. In the present embodiment I have illustrated the outline as printed on one side of the sheet, 2 representing generally the fuselage and 3 the aerofoils.

In the illustration the portions of the outline shown in solid lines indicate the lines of cut, while the portions shown in dotted

lines indicate the lines along which the blank is bent or folded. If desired, indicia 4 may be applied to the blank to assist the user in applying adhesive as in assembling the 5 fuselage or the aerofoils. The outline may be more completely applied to the sheet by printing a cabin on the fuselage and other distinguishing data that will bring out the 10 details of a commercial machine. The printing may be confined to one side of the sheet and in this event the entire surface may be colored or marked with the exception of the under surface of the elevators.

The cut out blank outlined on the sheet 1 15 comprises the essential parts of a toy aeroplane or glider, including the fuselage 2, the aerofoils 3, the elevators 5 and the rudder 6. The toy is developed along a center folding line 7 so that the sheet may be folded along 20 this line and both sides of the blank cut in one operation. I prefer, however, to cut along the solid lines with the sheet flat since this lessens the tendency to cut blindly and, of course, eliminates slipping of the folded 25 sections which would otherwise result in inaccurate cutting.

Assuming now that the blank has been cut from the sheet along the general outline as shown, the next step consists in cutting along 30 the lines 8 and 9 to separate the inner edges of the forward aerofoil sections 10 from the forward end 11 of the fuselage, thus permitting these sections to be folded back along the broken lines 12 to overlap the rear aero- 35 foil sections 13. It will be noted that by cutting along the lines 8 and 9 straps or tabs 14 are formed, the purposes and advantages of which will be described more fully hereinafter.

40 It will also be noted that by cutting along the lines 15 a lateral brace 16 is formed between the aerofoils and the fuselage, thus materially increasing the rigidity and ruggedness of the toy at a point where strength 45 is required.

The elevators and rudder are formed as outlined, it being only necessary to sever the blank along the lines 17 to separate these elements.

50 Assuming that the blank has been cut from the sheet as indicated and described, the next step in the construction of my aerial toy consists in folding the various parts along the broken lines. The blank is first folded down 55 along the line 7 and a drop of adhesive placed approximately at 4 and 4a on the inner walls of the complementary fuselage section to secure them together. The aerofoil sections are then bent downwardly along the lines 60 18 to a position approximately at right angles to the folded fuselage. The aerofoil sections 10 are then bent back along the lines 12 until the front edges overlie the rear edges of the sections 13, as shown in solid 65 lines in Fig. 3.

The aerofoils are formed to simulate as nearly as possible the aerofoils used in present day flying craft, that is, they are formed with a camber of the upper and lower surfaces. This may be accomplished in the 70 present invention by simply applying adhesive as at 4b, grasping the sections as shown in Fig. 3 and sliding the upper section forwardly over the lower section 13 to substantially the position indicated by dotted lines. 75 In this manner the upper and lower surfaces are secured together to form a cambered aerofoil, possessing a higher degree of rigidity than could be obtained by merely forming a cambered aerofoil of a single section from 80 the same material. After one of the aerofoils is formed the strap 14 extending therefrom is inserted between the sections 10 and 13 of the other aerofoil, which is formed in a similar manner. The strap of the latter 85 aerofoil extends out over the upper surface of the first aerofoil and may be secured thereto by applying adhesive and pressing the parts together.

It will be observed that the aerofoils may 90 be set or disposed at predetermined angles to the fuselage by securing the strap 14 at predetermined points along an imaginary line extending longitudinally of the aerofoil. If desired, indicia may be applied to the surface 95 of one of the sections 10 as at 20 to register with the edge or indicia 20a on the strap. The strap of the aerofoil first formed may be secured within the second wing by adhesive without applying pressure, it being sufficient 100 to secure the latter strap and allow the former to set.

The elevators are bent downwardly along the lines 21 at substantially right angles to the fuselage, although their angular adjustment may be varied at will and the trailing edges 22 may be bent independently of the remaining portions of the elevators. It is obvious that the rudder may be bent about a vertical axis, if desired, to control the horizontal line of flight.

In Fig. 2 I have illustrated means for shifting the center of gravity of the toy, which consists of applying a metal clip or the like 25 to the fuselage. The clip may be 115 removably attached and adjusted along the fuselage to shift the center of gravity.

It will be seen that by my invention an aerial toy such as a glider, may be constructed as a unitary structure from a single sheet of material. My invention provides considerable entertainment for children as well as grown ups, is highly educational, since it embodies many of the fundamental principles of aeronautics, and enables the user to study 120 these principles in actual practice. Furthermore, the invention is extremely simple of construction, requiring only that the outline of a complete aerial toy be defined on a single 125 sheet of material to be cut out and assembled 130

by merely folding certain portions of the cut out blank and applying adhesive thereto at indicated points.

In Fig. 7 I have illustrated a modification of my invention in which a portion 30 of the lower aerofoil sections may be cut and folded back and secured at their ends 31 to the fuselage to form an additional brace for the aerofoils. In this manner the assembled aerofoils may be braced as a unit against wobbling on the fuselage.

Instead of using a clip 25 as a means of weighting the nose of the toy, I may insert a longitudinal member between the folded sides 15 of the nose of the fuselage, securing the same in an adjusted position by any suitable means, thereby reinforcing the nose against distortion under sudden impact.

It is to be understood that various changes 20 may be made in the details of construction and arrangement of parts without departing from the spirit of the invention or the scope of the claims.

I claim:—

25 1. An aerial toy formed integrally from a sheet of material, comprising a fuselage and aerofoils extending therefrom, said aerofoils each comprising upper and lower surfaces of different widths to impart a camber to said 30 surfaces when they are secured together along their adjacent edges.

2. An aerial toy formed from a single sheet of material, including a fuselage and cambered aerofoils extending therefrom, said 35 aerofoils being integrally connected with the sides of the fuselage and comprising portions folded upon themselves, said folded portions being movable relatively laterally to impart a camber to said aerofoils and secured together near their adjacent free edges in said 40 relatively moved position to fix the camber of the aerofoils.

3. An aerial toy integrally formed from a single sheet of material, including a fuselage, 45 aerofoils extending therefrom, said aerofoils each comprising spaced upper and lower surfaces of different widths and secured together along their adjacent edges, and straps formed integrally with one of said surfaces 50 to enable said aerofoils to be set at a predetermined angular relation to the fuselage.

4. An aerial toy integrally formed from a single sheet of material, including a fuselage, 55 aerofoils extending therefrom, said aerofoils each comprising spaced upper and lower surfaces of different widths and secured together along their adjacent edges, and means integrally formed with said aerofoils and connecting the fuselage with each of said 60 aerofoils at a point intermediate the ends of said aerofoils for rigidly bracing the same.

5. A toy blank constituting a single sheet 65 of foldable material, said blank comprising a portion foldable upon itself to form a fuselage, portions extending from the sides of the

fuselage and constituting aerofoils, each of said aerofoils including a portion designed to be severed from the fuselage and bent over and secured along a longitudinal edge of said aerofoil portions to form cambered aerofoils. 70

6. An aerial toy blank including a portion foldable upon itself to form a fuselage, and portions extending outwardly from the sides of the fuselage portion and integrally 75 connected therewith to form aerofoils, said aerofoil portions each being foldable upon themselves to permit their respective free longitudinal edges to normally overlap one another, said overlapping folded portions being capable of relative movement to bring said respective edges into fixed register with each other to impart a camber to said aerofoils. 80

In testimony whereof, I hereunto affix my 85 signature.

JOHN B. TEGARTY.
